UNITED STATES PATENT OFFICE.

GEORGE W. LANCASTER, OF RICHMOND, VIRGINIA.

SOAP-SHAVING DEVICE.

Application filed July 13, 1925. Serial No. 43,184.

It is well known that in public places cakes of soap are left in the water causing considerable dissolving and going to waste and, furthermore, hotels and similar public places under law are required to change the soap every day, thereby avoiding any two or more persons using the same cake of soap, and hence preventing the carrying of skin diseases.

10 It is the purpose of the present invention to provide a device for holding a cake of soap, with means therein for grating the soap into shavings, the soap being so supported in a container as to prevent access to the cake of soap by the users. In this case persons in hotels and other similar public places may use the same cake of soap, without coming in contact with the cake itself, thereby making a great saving for the proprietors.

15 There are devices for grating cakes of soap, but many of these operate to move the soap toward the cutting or grating member, and in such instances means are provided to clamp the soap to followers, the followers having means to pierce the soap, and when the cake is reduced to a relatively small sliver, the sliver easily breaks or crumbles up, and in such cases the soap comes out in pieces, instead of shavings or in powdered condition. Other of such devices use rollers with sharp points thereon to contact with the cake of soap for grating the same, and again the soap will, when reduced to a relatively small sliver, break and discharge in pieces. Also, some of the devices have serrated surfaces which revolve against the face of the soap, but in these the spaces between the serrations cake up and prevent the serrations from cutting the soap. In other words, the serrated or corrugated surfaces eventually are so caked as to present a relatively smooth surface, which will merely smear against the face of the soap without cutting it.

20 It is the purpose of the present invention to avoid these difficulties and to provide a rotating, cutting, or shaving member, which at the same time of holding the cake in position will shave the soap down to substantially its last portion. In fact, the relatively small sliver that may be left will be retained in position and will be reduced almost to a mere nothing, at which time an

other cake of soap may be placed in position.

25 Some devices use springs to tension the holding means for the soap, for urging the soap toward the cutter. Such means are relatively old, and some of them are disposed to decrease the tension as the soap reduces in size, but the reducing of the tension of the springs in this instance is not for the same purpose as in the present case.

30 A still further purpose is to provide a moving follower, which also carries a removable shaving member, the follower being under tension of springs and adapted to clamp a cake of soap between an abutment and the shaving member, thereby enabling the cake of soap to be shaved off until it is 70 reduced to a very thin sliver, there being means on the abutment to retain this sliver in position until it is practically no more than a shaving itself, which will easily and conveniently discharge from the receptacle 75 or retainer.

35 A further purpose is to provide means for supporting the cake of soap on its sides, hence preventing the same from turning, the abutment having its face provided with means to assist in preventing the turning of the cake of soap, to insure uniform shavings which may discharge from the container or receptacle.

40 It is to be understood that the particulars herein given are in no way limitative and that, while still keeping within the scope of the invention, any desired modifications of detail and proportions may be made in the apparatus according to the circumstances.

The invention comprises further features and combinations of parts to be hereinafter set forth, shown in the drawings and claimed.

45 In the drawing:

Figure 1 is a view in perspective of the improved soap shaving device constructed in accordance with the invention;

Figure 2 is a vertical sectional view on the line 2—2 of Figure 1;

Figure 3 is a horizontal sectional view on the line 3—3 of Figure 2;

Figure 4 is a vertical sectional view on the line 4—4 of Figure 2;

Figure 5 is a view in perspective of the

follower which carries the revolvable shaving device.

Referring to the drawings, 1 designates a container which may be of any shape and size, preferably rectangular, as shown, and provided with a suitable conical discharge bottom 2, an opening 3, of sufficient size to permit of the discharge of shavings from the cake of soap 4. The container may be 10 constructed of any suitable material, preferably sheet metal, which may be nickel-plated, or otherwise finished off.

Arranged transversely of the container and vertically therein is an abutment wall 15 5. This abutment wall has side flanges 6, which may be brazed, spot welded, or otherwise secured to the interior faces of the sides of the container, or secured by screws and nuts, as indicated at 7 in Figures 1, 2 and 20 4. One face of the abutment wall is serrated or corrugated, as shown at 8, against which the cake of soap 4 may engage and be prevented from turning, when its surface is being shaved. The rear edge of the abutment wall is provided with a plurality of 25 lateral arms 9, which act to prevent excessive discharge of the shavings from the soap. The number of arms may vary according to the dimensions of the container 30 and the circumstances.

The abutment wall adjacent the sides of the container has guide openings 10, the lower portions of which are curved toward each other and terminate in tapered walls.

35 The openings 10 are provided for the purpose of guiding a follower 11, a detailed view of which is disclosed in Figure 5. The follower is constructed preferably of sheet metal, through not necessarily, and has side 40 arms 12, which are bent to form loops 13, which pass through the guide openings 10. Attached by eyes or similar means 14 to the rear wall of the container are tension coil springs 15, which pass through openings 16 in certain end walls of the loops 13, and have their other ends connected to the ends of screws 17, which are carried by the other end walls of the loops. The construction and arrangements of the springs 45 50 are such as to enable the springs to tension the follower and urge the same toward the abutment wall 5. A revolvable shaving member 18 is carried by the follower. The revolvable shaving member consists of a disk, constituting body 19, provided with radial cutting knives 20. Though only four knives are herein disclosed, it is obvious that any number of knives may be used. They are disposed on the disk or body to 55 60 assume positions perpendicular to the faces of the cake of soap, with their sharpened tapered cutting edges 21 in contact with the soap. The disk or body carries a shaft 22, which passes through and closely fits

in an opening 23, in one wall of the follower, 65 and also passes through an opening 24 in the front wall of the container. The shaft 22 carries a suitable handle 25, by which the shaft, together with the revolvable shaving member, may be rotated.

70 By reason of the follower being constantly under tension of the springs 15, urging the cutting edges of the knives or blades toward the soap, the soap is clamped between the shaving device and the abutment wall, and obviously, the corrugations 8 of the wall materially preventing the cake of soap from turning. It will be noted that the cake of soap will reduce in size as a result of every cutting action of the knives or blades of the 75 revolvable shaving member, and due to the constant tension of the springs, and the fact that there is no force created on the cake of soap itself (as in the other devices hereinbefore mentioned), the cake of soap will 80 reduce to a very thin sliver, not any more than what may be left between the corrugations or serrations 8 on the abutment wall. In this way a great saving is assured, while in devices previously mentioned the remaining portion of the cake of soap often breaks and discharges in relatively large pieces. Sometimes such pieces clog the discharge 85 opening of a container. With the present construction of device such difficulties are 90 readily avoided.

95 As the cake of soap reduces in size to a relatively small sliver the tension of the coil springs 15 likewise gradually decreases, thereby relieving excessive pressure of the 100 soap, and additionally preventing the same from breaking.

105 The adjacent sides of the opposed loops 13 (which are carried by the follower) have secured thereto spring blades 25, which extend downwardly and curve inwardly under the edge of the cake of soap, supporting the cake in position and a sufficient distance above the arms 9. Bumpers of any 110 suitable material, preferably rubber of any consistency, designated by the numeral 26, are secured to the upper portions of the adjacent faces of the spring blades 25. As previously stated, these bumpers are engaged by opposed edges of the cake of soap, thereby further preventing the movement of the soap. In fact, the downwardly and inwardly curved portions of the spring blades, the bumpers, together with the corrugations or 115 serrations 8, all act together to insure prevention of the turning of the cake of soap.

120 Where the abutment wall 5 is disposed, the container is divided into two compartments, the one 27, receiving the follower, the revolvable shaving member and the cake 125 of soap, the other 28, constituting means for the reception of an additional cake of soap, to be installed in position between

the shaving device and the abutment when the first cake has been used.

The container has a portion of its rear open as at 29, and this opening, when the 5 container is disposed adjacent the face of a wall, is closed by the wall. However, the opening 29 is provided for the purpose of installing the various operating parts of the soap shaving device in position. The side 10 walls of the container adjacent their rear edges have lateral ears 30, which receive securing means, as shown, to fasten the container to a wall or other stationary support.

The upper part of the container is open, 15 the same being provided with a cover or lid 31, which is hingedly mounted as at 32 to one side of the container. The lid or cover has a hasp 33 through which a staple 34 may pass for the reception of a padlock or other suitable locking device whereby 20 the cover or lid may be retained in a closed position and hence prevent access to the soap, other than receiving the shavings from the discharge opening of the container.

25 The essential features of the present device consists in the idea of a shaving device acting as a clamping medium, and moving with the follower and in the direction of the soap, which is constantly reducing, thereby 30 avoiding any tension of the soap whatever that would cause the same to fracture or crumble up when it reduces to a smaller compass. Another essential feature is the idea of the springs reducing in tension as the 35 cake of soap decreases in size, hence insuring prevention of fracturing or crumbling up of the soap.

By grasping the handle 25 the shaft 22 may 40 rotate and impart movement to the disk 45 which carries cutting knives 20. It is possible to rotate the shaft 22 in either direction, causing the cutting edges of the knives 20 to operate against the surface of the soap, and thereby shave the same, the shavings discharging through the discharge opening of the container.

The invention having been set forth what is claimed is:

1. A soap shaving device, comprising a 50 container with an internal abutment, and a tension follower means carrying a slidable but revolvable shaving device to clamp a cake of soap in position between the abutment and the device, thereby shaving the 55 surface of the soap.

2. A device for the purpose indicated, 60 comprising a container, an abutment therein, a follower means operable in the container toward the abutment, a revolvable shaving element carried by the follower means and means for drawing the revolvable shaving element and the follower means toward the soap with gradually decreasing tension as the soap reduces in size, the shav-

ing element being movable away from the 65 abutment through the medium of the follower means to permit another cake of soap to be inserted.

3. A device for the purpose indicated, 70 comprising a container, an abutment therein dividing the container into a storage compartment and a soap shaving compartment, and follower means guided in the abutment, a revolvable shaving element operable with the follower means and between which and the abutment the cake of soap may be positioned, a tensioning device connected to the 75 wall of the container and in turn to the follower means for tensioning the latter decreasingly as the shaving element moves toward the abutment and the cake of soap reduces in size.

4. A soap shaving device, comprising a 80 container with an internal abutment and a tension follower means carrying a revolvable shaving device to clamp a cake of soap in position between the abutment and the device, thereby shaving the surface of the soap, and means depending from the opposed portions of the follower means and directed toward each other for supporting the lower edge of the cake of soap.

5. A device for the purpose indicated, 85 comprising a container, an abutment therein, a follower means operable in the container toward the abutment, a revolvable shaving element carried by the follower means, and means for drawing the revolvable shaving element and the follower means toward the soap with gradually decreasing tension as 90 the soap reduces in size, and means depending from the opposed portions of the follower means and directed toward each other for supporting the lower edge of the cake of soap.

100

6. A device for the purpose indicated, 105 comprising a container, an abutment therein dividing the container into a storage compartment and a soap shaving compartment, and follower means guided in the abutment, a revolvable shaving element operable with the follower means and between which and the abutment the cake of soap may be positioned, a tensioning device connected to the 110 wall of the container and in turn to the follower means for tensioning the latter decreasingly as the shaving element moves toward the abutment and the cake of soap reduces in size, and means depending from the

115 opposed portions of the follower means and directed toward each other for supporting the lower edge of the cake of soap.

7. A device for the purpose indicated, 120 comprising a container, an abutment therein dividing the container into a storage compartment and a soap shaving compartment, and follower means guided in the abutment, a revolvable shaving element operable with

- the follower means and between which and the abutment the cake of soap may be positioned, a tensioning device connected to the wall of the container and in turn to the follower means for tensioning the latter decreasingly as the shaving element moves toward the abutment and the cake of soap reduces in size, and means carried by the abutment and also means carried by opposed parts of the follower means to prevent turning of the cake of soap.
8. A device for the purpose indicated, comprising a container, an abutment therein, a follower means operable in the container toward the abutment, a revolvable shaving element carried by the follower means, and means for drawing the revolvable shaving element and the follower means toward the soap with gradually decreasing tension as the soap reduces in size, and retarding devices projecting from the lower part of the abutment in the path of the discharging shavings from the soap, thereby preventing excessive discharge of the shavings.
9. A device for the purpose indicated, comprising a container, an abutment therein, a follower means operable in the container toward the abutment, a revolvable shaving element carried by the follower means, and means for drawing the revolvable shaving element and the follower means toward the soap with gradually decreasing tension as the soap reduces in size, and retarding devices projecting from the lower part of the abutment in the path of the discharging shavings from the soap, thereby preventing excessive discharge of the shavings, and

means on the abutment to prevent turning or displacement of the cake of soap.

10. A soap shaving device, comprising a container with an internal abutment, and a tension follower means carrying a revolvable shaving device slidable with respect to the follower means to clamp a cake of soap in position between the abutment and the device, thereby shaving the surface of the soap, said device having manual means slidable with regard to the container to move the device and the follower means against the tension means of the follower to permit insertion of the soap.

11. A soap shaving device comprising a container with an internal abutment, a tensioned follower means, a shaving element mounted in and for movement slidable with regard to the follower means and the container to clamp a cake of soap between the abutment and the element, whereby the follower means may be moved relative to the container against its tensioning action to permit the insertion of a cake of soap.

12. A soap shaving device comprising a container with an internal abutment, a tensioned follower means, a shaving element mounted in and for movement slidable with regard to the follower means and the container to clamp a cake of soap between the abutment and the element, whereby increased pressure may be applied upon the device independently of the follower means for increasing the size of the shavings of soap.

In witness whereof, the inventor's signature is hereunto affixed.

GEORGE W. LANCASTER.
